DISPLAY TABLE

Peter Zellner, New York, N.Y., assignor to The Metropolitan Museum of Art, New York, N.Y., a corporation of New York

Filed June 4, 1969, Ser. No. 17,515

Term of patent 14 years

Int. Cl. D6—01

U.S. Cl. D80—2

FIG. 1 is a perspective view of a display table embodying my new design;

FIG. 2 is an elevational view thereof;

FIG. 3 is a top plan view thereof;

FIG. 4 is a cross-sectional view taken along line 4—4 of FIG. 1;

FIG. 5 is a perspective view of a modified form of the display table shown in FIG. 1;

FIG. 6 is an elevational view of a second modified form of the display table shown in FIG. 1, the difference being in the length of the support legs; and

FIG. 7 is a perspective view of a third modified form of the display table shown in FIG. 1.

The broken line representation in FIGS. 1, 2, 5, 6 and 7 indicates a display case, such as for example a clear plastic case, shown for purposes of illustration only.

I claim:

The ornamental design for a display table, substantially as shown and described.
